SAFETY SHUTTER OR GUARD ATTACHMENT FOR CLOTHES WRINGERS

Norman Edward Ryckman, Hamilton, Ontario, Canada, assignor to The Coffield Washer Company Limited, Hamilton, Ontario, Canada

Application September 15, 1933, Serial No. 689,502

8 Claims. (Cl. 68—32)

The invention relates to a safety shutter or guard attachment for clothes wringers, as described in the present specification and illustrated in the accompanying drawings which form a part 5 of the same.

The invention consists essentially of the novel features of construction pointed out broadly and specifically in the claims for novelty following a description containing an explanation in detail 10 of an acceptable form of the invention.

The objects of the invention are to avoid accidents which ordinarily occur in the operation of clothes wringers, where no safety attachment is applied due to the entanglement of the user's 15 wearing apparel or hair of the head, or hands coming into engagement with the rollers and thereby causing considerable harm; to facilitate the operator's work in wringing the clothing by providing a safety shutter which will act as a 20 guide for the clothing both in entering the wringer and leaving it as well as devising a means whereby the water from the rinsed clothing will be drained to its respective tub as desired; to furnish a safety shutter attachment which may be either automatic or manual, that can be easily attached to 25 any form of clothes wringer and of simple and durable construction, comparatively few parts; and generally to provide an attachment for clothes wringers which will act as a dual purpose 30 in that it will guard the attendant from danger in personal contact with the rollers of the wringer and at the same time form a guide for the clothes into the wringer as well as a means for leading out the direction of the clothing from the wringers on the opposite side.

In the drawings, Figure 1 is a front elevation of a wringer showing the attachment secured thereto.

Figure 2 is an end elevation of the wringer taken 40 in the direction of arrow "A" in Figure 1.

Figure 3 is a vertical sectional view of the wringer and attachment taken on the lines 3—3 in Figure 1.

Figure 4 is a front elevational view of the attachment.

Figure 5 is an end view of the attachment.

Figure 6 is a fragmentary front elevational view of the rolls showing the eccentric and the trip in position on the roll shafts.

Figure 7 is an end view of Figure 6 showing the eccentric and the trip in operation.

Figure 8 is an enlarged end elevation showing means for supporting the end plates by the spring attachment.

Figure 9 is an end elevational view of the rolls and operating parts about to trip the attachment.

Like numerals of reference indicate corresponding parts in the various figures.

Referring to the drawings, there are two attachments as indicated by the numerals 13 and 14

which are secured to the clothes wringer on opposite sides and on each of the attachments are formed a pair of end plates 15 and 16 which are connected together by means of the upper and lower shutters 17 and 18 and the lower portion of the end plates 15 and 16 are secured by means of the pins 19 and 20 to the flanges 21 and 22 of the tilting drain board 23 which is situated beneath the rolls 24 and 25 of the wringer 26.

The roll shafts 27 and 28 of the rolls 24 and 25 have an eccentric 29 and a trip mechanism 30, the trip mechanism being on the lower shaft while the eccentric is on the upper shaft, and the trip mechanism is adapted to engage with the dog 31 which is mounted to one of the end plates and is for the purpose of tilting the tilting drain board 70 for changing the position of the shutters of one attachment from a feeding device to a scraping and stripping device, and simultaneously changing the direction of flow for the water on the 75 drain board.

In the operation of the wringer, it is used the very same as other wringers, that is to say, the clothes are fed in one side of the rolls and discharged at the other side, the only difference 85 being that the hazard of the clothes becoming wrapped around the rolls or the operator's hands being caught therein is completely removed, rendering the wringer practically fool proof.

As will be seen on Figure 3, the clothes are being 90 fed from the left side and discharged from the right side. When in this position it will be noted that the upper and lower fins of the safety shutter on the feed side are out of engagement with the rolls while the fins on the right or discharge side 95 are performing their scraping action, thus preventing any chance of the clothes becoming wrapped around the upper or lower rolls.

The water shutter at the bottom and the drain board takes care of the waste water. It will be 100 seen on Figures 7 and 9, the position of the safety shutter is governed by the direction in which the rolls are rotating. This is accomplished by means of the dog 31 which is pivotally mounted on one end of the safety shutter and the double ended 105 cam or trip lever 30 which is rigidly mounted on one end of the roll shaft 28.

It will be noted on Figure 7 when the roller is rotated in the direction of the arrow, the position of the safety shutter will remain unchanged because the double ended trip cannot engage the dog while travelling in the direction indicated. However, when the roll is rotated in the opposite direction as in Figure 9, the trip will engage the dog and trip the shutter as shown, upwardly forcing the fins of the shutter into their scraping 110 position.

The eccentric 29 which is mounted on the upper roll shaft provides means for a feeding action upon the clothes. That is to say, it provides a 115 120

back and forth motion to the upper fin of the safety shutter, thereby aiding the clothes in passing through the rollers. The inner edge of the ends of the safety shutter is in engagement with this eccentric and being pivotally held in position, must necessarily stay in engagement and follow its course in rotation, thus providing the feeding motion to the upper fin.

The springs 38 and 39 are inserted and held 10 at each end within the tube 40 which is pivoted to the end plates 15 and 16 by means of the pins 41 and 42 slidable in the slots 43 and 44 in order to permit the expansion or contraction of the attachments and provide the pressure required 15 to keep the shutters against the rollers. The end plates 15 and 16 have the set screws 45 and 46 for adjustment of the end plates so as to tighten or loosen the shutter against the rollers.

There are many various ways and arrangements whereby the tripping action can be accomplished without departing in any way from the essential features of this invention, and the applicant does not desire to confine himself in any way to the acceptable form as shown.

25 There are other ways also in which guards or shutters could be attached to a wringer to provide a feeding device on one side and a stripping device on the other.

It will be seen from the foregoing that the 30 device is practical, automatic in action and to all intents and purposes fool proof construction, tending to provide to users of electric washers, a sense of freedom as far as the wringer is concerned, from possible danger to themselves or 35 damage to the clothes being wrung, heretofore unknown.

Another important feature in this construction is in the way in which the clothing can be automatically fed between the rollers by means of the 40 guide plate which also acts as a guard so that there is no necessity, as occurs in ordinary wringers, to guide the clothing between the rollers with the operator's hands thereby eliminating to a very great extent accidents that are caused thereby.

45 The attachments as heretofore mentioned may be applied to any form of clothes wringer and although operated through the movements of the rollers which in turn are operated by its own mechanism yet the attachments are independent 50 with the actual operations of the wringer such as in the tripping mechanism for releasing the pressure of the rollers.

What I claim is:

1. In a safety shutter or guard attachment for 55 clothes wringers, a plurality of rollers and means for operating said rollers, a drain board tiltedly secured beneath the rollers, safety shutters mounted on said wringer on either side of the rollers having fins adapted to form guides for the clothing as well as guards.

60 2. In a safety shutter or guard attachment for clothes wringers, a pair of attachments mounted on either side of the clothes wringer having shutters extending therefrom forming guards and 65 adapted to guide the clothing through the wringer, means connected to said attachments for lowering or raising the shutters in respect to one another and operated through the movements of the rollers.

70 3. In a safety shutter or guard attachment for clothes wringers, an attachment formed of shutters situated on either sides of the clothes wringer

and mounted on a drain board situated beneath the rollers and tilted, and means on said rollers for changing the position of the shutters of the attachments and coincidentally tilting the drain board.

80 4. In a safety shutter or guard attachment for clothes wringers, a plurality of rollers, means for operating said rollers, a tilttable drain board situated beneath the rollers, an attachment formed of a plurality of safety shutters situated on either side of the rollers and mounted on the drain board, and means mounted on said rollers for tilting the position of the attachments for changing the position of the shutters thereof, and coincidentally tilting the position of the drain board.

85 5. In a safety shutter or guard attachment for clothes wringers, a plurality of rollers, a drain board mounted beneath said rollers, a pair of attachments mounted on said drain board on either side of the rollers, formed of end plates connected together by shutters situated at an angle to form a guard for the operator as well as a guide for the clothing to be wrung on the one side, and a guard and stripping water shed on the other side for directing the egress of the clothing passing 100 through the rollers, and means on said rollers for reversing the positions of the attachments and coincidentally changing the position of the drain board beneath the rollers.

90 6. In a safety shutter or guard attachment for 105 clothes wringers, a plurality of rollers, means for operating said rollers, a drain board beneath said rollers, guard members situated on each side of the rollers covering the ingress and egress space formed between the rollers, said guard members 110 having vanes projecting downwardly at an angle to form a feeder on the one side and a stripper on the other side for the clothing which is to be passed through the rollers, and means for reversing the feeder and stripper to opposite sides 115 through the direction of travel of the rollers and coincidentally changing the direction of flow of the drain board.

7. In a safety shutter or guard attachment for 120 clothes wringers, a pair of rollers, a drain board 125 beneath said rollers, an eccentric mounted to one of the rollers and a trip mechanism mounted on the other of said rollers, means for operating said rollers, a pair of attachments situated on either side of said rollers and secured to said tilting drain board, a plurality of vanes projecting inwardly from said attachment to form a feeder and a stripper on opposite sides of the rollers for guiding the clothing passing through the rollers, and a dog mounted on one of said attachments adapted 130 to be engaged by said trip mechanism for reversing the angles of the vanes of the attachment and coincidentally changing the tilt of the drain board.

8. A safety shutter or guard attachment for 135 clothes wringers, a plurality of rollers, means for operating said rollers, a drain board tiltedly secured beneath the rollers, an attachment formed of shutters situated on either side of the clothes wringer and mounted on said drain board and 140 independently secured from the means for operating said rollers, said roller operating means adapted to change the position of the shutters of the attachment and coincidentally tilt the drain board.

NORMAN EDWARD RYCKMAN.
